UNITED STATES PATENT OFFICE.

WILLIAM A. BARRY, OF KITTANNING, PENNSYLVANIA.

COLLAPSIBLE DRUM.

1,223,237.

Specification of Letters Patent.

Patented Apr. 17, 1917.

Application filed June 7, 1915. Serial No. 32,723.

To all whom it may concern:

Be it known that I, WILLIAM A. BARRY, a citizen of the United States, residing at Kittanning, in the county of Armstrong and State of Pennsylvania, have invented new and useful Improvements in Collapsible Drums, of which the following is a specification.

This invention relates to drums.

10 The principal object of the invention is the provision of a drum so constructed that it may be knocked down and folded into compact form for carrying from place to place conveniently.

15 Another object of the invention is to provide a folding drum which may be readily knocked down or folded into compact form or set up into operative position without in any way affecting the tone of the instrument.

20 Further objects of the invention will appear as the following specific description is read in connection with the accompanying drawings which form a part of this application, and in which:—

Figure 1 is a perspective view of the drum in operative position.

Fig. 2 is a similar view with the parts in folded position.

25 Fig. 3 is a side elevation showing one of the hoops or bands in partially folded position.

Fig. 4 is a top plan view of one of the hoops in completely folded position.

30 Fig. 5 is a top plan view of the drum shell in partly folded position.

Fig. 6 is a detail perspective view showing the meeting ends of the drum shell in separated relation.

35 Fig. 7 is a detail vertical sectional view taken through the drum.

Fig. 8 is a view showing one of the hoops partly folded.

40 Fig. 9 is a similar view showing the arrangement prior to the complete folding of the hoop.

In the specific embodiment of the invention as illustrated herein, the drum consists generally of a shell 1, hoops or bands 2, connecting rods 3 and heads 4 secured to the bands. The shell comprises a plurality of arcuate sections 5, 6, 7 and 8, hinged together as shown and arranged so that when the free edges of the sections 5 and 8 are brought together a circular tube will be produced. The section 5 is preferably pro-

vided with dowel pins 9 adapted to fit in the sockets 10 of the section 8.

As the upper and lower hoops are identical, it will be necessary therefore, to describe only one. These hoops are formed of semi-circular sections 11 and 12 connected together by the hinge 13 which permits one of the sections to fold over upon the other section. Each section consists of 65 separate parts *a* and *b* connected together by a hinge 14 which permits the free ends of the folded sections to be brought together thereby producing an elliptical package as is shown in Fig. 2. Each section 11 70 and 12 is provided with a channel or recess in its outer surface as shown at 15 to receive the peripheral edge of the drum head 4 which is stretched around the hoop and extends beneath the same and into the recess 75 where it is securely held by metallic strips 17 fastened to the band or hoop by screws 18 or other similar fastening devices. The strip 17 for each section is divided into two parts so as to permit of the folding of the 80 parts *a* and *b* of the sections of the band.

Each hoop section carries a plurality of laterally extending slotted lugs 19 provided with a circular recess 20 in their outer faces arranged to receive the hub of the wing 85 nuts 21 threaded upon the ends of the tension rods 22. When the wing nuts are loosened at either end of the drum, the rods may be removed from the lugs 19 and the parts folded as shown in Fig. 3. As shown 90 in Fig. 7, the hoops or bands are of slightly larger diameter than the shell so as to fit over opposite ends thereof whereby when the hoops are drawn together by the nuts and tension rods the head resting upon the 95 edges of the shell will be placed under tension and thereby tuned. In folding the drum, the wing nuts are first loosened and the rods removed. The hoops or bands are then disconnected from opposite ends of the 100 shell and folded in a manner before described. The shell is then folded and the bands placed upon opposite ends of the shell with the head lying within the folded sections of the shell.

105 What is claimed is:—

1. In a drum, a foldable shell, head carrying bands for opposite ends of the shell, each of said bands comprising a pair of hingedly connected sections, each of said 110 sections consisting of hinged parts pivoted on an axis at right angles to the axis of the

sections, heads carried by the bands, slotted lugs carried by the bands and tension rods fitted into the slots of the lugs and having wing nuts threaded upon opposite ends thereof.

2. A collapsible drum comprising a segmental sectional shell, said sections being hinged together to provide a substantially oblong package when folded, pins projecting from the edge of one of the end sections and adapted to be received in recesses in the meeting edges of the adjacent section when the shell is in set up position, head carrying bands for the opposite ends of the shell, each of said bands comprising a pair of

hingedly connected sections, each of said sections consisting of hinged members pivoted on an axis at right angles to the axis of the sections, heads carried by said bands, slotted lugs projected from the bands, tension rods fitted in the slots of said lugs, and nuts threaded upon the opposite ends thereof. 20

In testimony whereof I affix my signature in presence of two witnesses.

WILLIAM A. BARRY.
